UNITED STATES PATENT OFFICE

DELAVAN M. BALDWIN, OF NEW YORK, N. Y.

DESIGN FOR A FIREPLACE SCUTTLE

Application filed April 13, 1931. Serial No. 39,461. Term of patent 3½ years.

To all whom it may concern:

Be it known, that I, DELAVAN M. BALDWIN, a citizen of the United States, residing at New York, in the county of New York and State of New York, have invented a new, original, and ornamental Design for a Fireplace Scuttle, of which the following is a specification, reference being had to the accompanying drawings, forming part thereof.

Fig. 1 is a perspective view of a fireplace scuttle, showing my new design.

Fig. 2 is a front elevational view of the same.

Fig. 3 is a top plan view of the same.

I claim:

The ornamental design for a fireplace scuttle, as shown.

In testimony whereof I have affixed my signature.

DELAVAN M. BALDWIN.
